(57) **CLAIM**

The ornamental design for a brush handle, as shown and described.

DESCRIPTION

FIG. 1 is a perspective view of a brush handle showing my invention;

FIG. 2 is a front side view thereof;

FIG. 3 is a back side view thereof;

FIG. 4 is a left side view thereof, the right side being a mirror image thereof;

FIG. 5 is a top side view thereof; and,

FIG. 6 is a perspective view of the brush handle of FIGS. 1-5 shown with a different brush head in broken lines.

The broken lines of the hole, the bristles, and the brush head section are for illustrative purposes only and form no part of the claimed design.
